UNITED STATES PATENT OFFICE.

SELIM D. HATHAWAY, OF COLDWATER, MICHIGAN.

GATE.

SPECIFICATION forming part of Letters Patent No. 629,360, dated July 25, 1899.

Application filed April 25, 1899. Serial No. 714,441. (No model.)

To all whom it may concern:

Be it known that I, SELIM D. HATHAWAY, a citizen of the United States, residing at Coldwater, in the county of Branch and State of Michigan, have invented a new and useful Gate, of which the following is a specification.

The invention relates to improvements in gates.

The object of the present invention is to improve the construction of that class of swinging gates which are connected with a hinge-post by a swinging frame or hanger and which are adapted to be arranged at either side of the latter and to provide a simple, inexpensive, and efficient gate of this character which may be opened from either end and in either direction to suit the convenience of the person operating it.

Another object of the invention is to improve the construction of the latch mechanism and to enable the gate to be quickly adjusted to counteract sagging and to elevate it to clear obstructions or to provide a passage-way for small animals.

The invention consists in the construction and novel combination and arrangement of parts hereinafter fully described, illustrated in the accompanying drawings, and pointed out in the claims hereto appended.

In the drawings, Figure 1 is a perspective view of a gate constructed in accordance with this invention. Fig. 2 is a side elevation showing the opposite side of the gate. Fig. 3 is a detail vertical sectional view illustrating the construction for adjusting the gate, the latter being arranged at right angles to the swinging frame or hanger. Fig. 4 is a detail horizontal sectional view illustrating the manner of adjustably mounting the inner keeper on the swinging frame or hanger. Fig. 5 is a detail perspective view of the keeper of the latch-post.

Like numerals of reference designate corresponding parts in all the figures of the drawings.

1 designates a gate preferably constructed of horizontal rails 2 and vertical bars 3 and 4, arranged in pairs at the ends and center of the gate and receiving the horizontal bars 5 or rails between them; but the gate may be constructed in any other manner, if desired. The gate is centrally mounted on the outer

end of a swinging frame or hanger 5, which is substantially triangular, being composed of upper and lower inclined bars 6 and 7 and vertical bars 8, connecting the inner ends of the bars 6 and 7 and arranged parallel, as shown, to provide a vertical space or opening for the purpose hereinafter described. The outer ends of the bars 6 and 7 are separated and are connected by short vertical pieces 9, located near the outer extremities of the said bars. The hanger is provided at its inner end with upper and lower eyes 10 and is hinged to corresponding eyes 11 of a post 12 by a removable pintle-rod 13, which will enable the gate and the hanger when detached to be readily inverted, for a purpose hereinafter described.

The outer ends of the bars 6 and 7 of the swinging frame or hanger are provided with registering perforations for the reception of a vertical pivot or pintle 14 of a bracket 15, which is provided near its upper portion with a horizontal pivot 16, upon which the gate is hung; and the said pivot 16, which passes through the bars 4 and the adjacent horizontal rail of the gate, is located above the center thereof and is threaded for the reception of a nut 17. By locating the pivot 16 above the center of the gate the latter, together with the hanger, may be inverted to provide an elevated gate for clearing heavy snows and similar obstructions. The bracket, which may be constructed of any suitable material, is provided at its top and bottom with horizontal arms, which are perforated for the reception of the pintle 14 and which receive a sleeve or tube 18. The tube 18, which extends from the top to the bottom of the bracket, passes through the perforations of the outer ends of the bars 6 and 7 and forms an antifriction-bearing, and the space between the arms of the bracket provides for a considerable adjustment of the gate, the vertical pintle being adapted to be moved up and down through the perforations of the swinging frame or hanger. The gate is clamped at any desired vertical adjustment by means of a clamping-bar 19, guided between the vertical connection portions 9 of the hanger and provided at its outer end with an opening 20, through which the tube passes. The inner portion of the clamping-bar is adapted to be drawn up

ward to bind the tube in the perforation or opening of the outer end of the bar 19, and the frictional clamping action is sufficient to hold the gate in its adjusted position. The 5 clamping-bar is secured in its engaging position by a loop 22, of cord, wire, or any suitable material, and the loop 22, which passes around the clamping-bar and the upper bar 6 of the hanger, is adapted to be moved longitudinally of the said bar 6 to secure and release the pintle. The bar 6 and the clamping-bar diverge inwardly toward the hinge-post, and it will be clear that by sliding the loop in the direction of the pintle 13 the 10 clamping-bar will be forced upward toward the bar 6, whereby the tube will be firmly clamped. The clamping of the tube by the bar 19 does not affect the pivotal movement of the gate, which is adapted to swing both 15 vertically and horizontally. This construction enables one or both ends of the gate to be raised to counteract sagging and also to clear obstructions or to provide a passage for small animals.

25 The ends of the horizontal bars or rails of the gate project beyond the vertical end bars of the gate and are adapted to interlock with double keepers 23 and 24, mounted, respectively, on a latch-post 25 and on the inner end 30 of the swinging frame or hanger, and these latches, which project from opposite sides of the latch-post and the hanger, are provided in their projecting portions with recesses, which are adapted to receive the end bars, whereby 35 the gate is locked in its closed position. The double keeper 23, which is mounted on the latch-post, is centrally recessed to provide shoulders 27 for engaging the side faces thereof, whereby it is prevented from turning on 40 the fastening device 28. The fastening device 28, which may consist of a screw, bolt, or any other suitable fastening device, is adapted to secure the double keeper 23 to the latch-post at the desired elevation, and the said latch-post is preferably provided with a series of 45 perforations for the reception of the fastening device to facilitate such adjustment.

The double keeper 24, which is mounted on the hanger, is provided at its center with recesses 29 for the reception of the adjacent vertical edges of the bars 8 to prevent the keeper 24 from rotating on the bolt 30, which passes through the space between the bars 8. The head of the bolt 30 engages the double keeper 55 24, and its other end, which is threaded, receives a nut 31, which bears against a plate 32. The plate 32, which is disposed opposite the double keeper, spans the vertical opening or space between the bars 8 and enables the said keeper 60 24 to be firmly mounted on the inner portion of the hanger. By loosening the bolt 30 the double keeper 24 may be adjusted vertically to any position on the bars 8 between the upper and lower bars 6 and 7.

65 The gate is adapted to be arranged at either side of the hanger and the latch-post, and it is provided with a pair of sliding latch-bars

33, guided between the vertical bars of the gate and located between two of the horizontal rails. The inner portions of the sliding latch-bars, which extend beyond the center of the gate, overlap each other, and the outer engaging portions 34 are beveled or wedge-shaped and adapted to be interposed between the lower edges of the keepers and the supporting horizontal rail, whereby the ends of the gate are locked against upward and downward movement. The longitudinal movement of the reciprocating latch-bars is limited by lateral projections 36, consisting of pins or other suitable fastening devices passing through the latch-bars and located between the central and end bars of the gate. The latch-bars, by being arranged as just described, are adapted to be operated at either side of the center of the gate, which will be found of great advantage to persons driving.

The gate is provided at a point below the main latch-bars 33 with short latches 37, having beveled or wedge-shaped outer portions, 80 and provided at the inner and outer sides of the end bars with pins 38, projecting from opposite sides of the latches and limiting the inward and outward movement thereof. These short latches are designed to be used when the gate is elevated, and they are adapted to engage beneath the double keepers similar to the main latch-bars. In order to increase the adjustment of the gate, a vertical series of perforations 40 is provided for the reception of the horizontal pivot of the bracket. In ordinary adjustments of the gate the clamping device and the vertical tube or sleeve will be found sufficient, but in extreme adjustments the perforations are advantageous.

105 The invention has the following advantages: The gate, which is evenly balanced, is adapted to be readily handled, and as it is capable of a vertical range of adjustment and a vertical and horizontal pivotal movement it may be arranged at any desired elevation and at either side of the hanger and the latch-post. The gate may be opened in either direction and from either end, and as the inner double latch is located at the inner edges of 110 the rear vertical bars 8 of the hanger such vertical bars may be increased in width without unbalancing the gate or making it large and unwieldy. The reciprocating latch-bars, which have their inner ends overlapping, are adapted to be readily operated at either side of the center of the gate, and their outer ends are adapted to be firmly wedged beneath the keepers, so that the gate cannot be accidentally lifted out of engagement with the same. 115 The short latches, which are located at a point beneath the main latches, are designed to engage the keepers when the gate is in an elevated position, and the keepers of both the latch-post and the hanger are capable of vertical adjustment. The pintle-rod, which detachably connects the hanger to the hinge-post, permits both the hanger and the gate to be readily detached, and as the horizontal

pivot of the gate is located at a point above the center the gate when removed may be reversed to bring the pivot below the center, and thereby elevate the gate, so that the same 5 may pass over snowdrifts or other obstructions. The gate is adapted to have either or both ends adjusted vertically, and the clamping device, which is mounted on the outer portion of the swinging frame or hanger, is 10 capable of ready adjustment and is adapted to securely hold the vertical tube at any point.

Changes in the form, proportion, size, and the minor details of construction within the scope of the appended claims may be resorted 15 to without departing from the spirit or sacrificing any of the advantages of this invention.

What is claimed is—

1. The combination of a hanger, a gate, a 20 bracket mounted on the gate and adapted to support the same, a vertical pintle carried by the bracket and arranged in a vertical opening of the hanger, a clamping-bar carried by the hanger and provided with an opening receiving the vertical pintle, said clamping-bar being adapted to bind against the pintle to 25 secure the gate at the desired adjustment, and means for holding the clamping-bar in engagement with the vertical pintle, substantially as described.

2. The combination of a hanger having an opening, a bracket provided with a vertical pintle arranged within the opening of the hanger, a gate mounted on the bracket, a clamping-bar carried by the hanger and having 35 an opening to receive the vertical pintle, said clamping-bar being arranged at an angle to a portion of the hanger, and a sliding loop mounted on such portion of the hanger and 40 receiving the clamping-bar, substantially as described.

3. The combination of a swinging frame or hanger having upper and lower converging bars spaced apart at their adjacent ends and 45 provided with connecting-pieces, a bracket having a vertical pintle passing through the adjacent ends of the converging bars, a gate mounted on the bracket, a clamping-bar located between the converging bars and guided 50 by the connecting-pieces and provided with an opening receiving said pintle, and means for securing the clamping-bar in its engaging position, substantially as described.

4. The combination of a swinging frame or 55 hanger provided at its outer end with an opening, a gate, a bracket carrying the gate and provided with a vertical pintle-rod, a sleeve or tube arranged on the pintle-rod and

passing through the opening of the hanger, and a clamping-bar carried by the hanger and 60 engaging the vertical tube, substantially as described.

5. The combination of a swinging frame or hanger provided at its outer end with an opening, means for detachably hinging the 65 inner end of the frame or hanger to a support, a bracket provided with a removable pintle-rod, a tube or sleeve arranged on the removable pintle-rod and passing through the opening of the frame or hanger, and a clamping- 70 bar carried by the frame or hanger and engaging the tube or sleeve, substantially as described.

6. The combination of a swinging frame or hanger, a gate hinged between its ends to the 75 same, and the reciprocating latch-bars slidingly mounted on the gate and having overlapping inner portions extending beyond the center of the said gate, the outer ends of the latch-bars being adapted to engage keepers 80 of the frame or hanger and of the latch-post, substantially as described.

7. The combination of a swinging frame or hanger provided at its inner end with vertical parallel bars spaced apart, a gate hinged between its ends to the outer end of the hanger or frame, a double keeper mounted on the inner portion of the frame or hanger and provided with recesses forming shoulders and receiving the adjacent edges of the said vertical bars, and a fastening device connected with the keeper and passing through the space between the vertical bars and engaging the latter, whereby the keeper is adjustably secured to them, substantially as described. 95

8. The combination of a swinging frame or hanger, a gate mounted thereon and composed of horizontal rails and vertical bars arranged in pairs, the main latch-bars mounted between and guided by the vertical bars and having wedge-shaped outer portions and provided with inner overlapping portions extending beyond the center of the gate, the short latches mounted on the gate at the ends thereof and guided by the vertical bars of the 105 same, and the double keepers designed to be mounted on the swinging frame or hanger and on a latch-post, substantially as described.

In testimony that I claim the foregoing as my own I have hereto affixed my signature in 110 the presence of two witnesses.

SELIM D. HATHAWAY.
